Primary Examiner — Ricky Pham(74) *Attorney, Agent, or Firm* — Husch Blackwell LLP(57) **CLAIM**

We claim the ornamental design for a mixer, as shown and described.

DESCRIPTION

FIG. 1 is a perspective view of a mixer;

FIG. 2 is a left side elevation view of the mixer;

FIG. 3 is a rear elevation view of the mixer;

FIG. 4 is a right side elevation view of the mixer;

FIG. 5 is a front elevation view of the mixer;

FIG. 6 is a top plan view of the mixer; and,

FIG. 7 is a bottom plan view of the mixer.

Broken lines shown in the drawing views are included for illustrative purposes only, and form no part of the claimed design.
